US0D1011077S

(12) **United States Design Patent** (10) Patent No.: **US D1,011,077 S**
(45) Date of Patent: ** Jan. 16, 2024

(54) **TOOTHBRUSH HOLDER**

(71) Applicant: **Shenzhen Baohongjia Technology Co., Ltd.**, Shenzhen (CN)
(72) Inventor: **Lihua Yu**, Ningbo (CN)
(73) Assignee: **Shenzhen Baohongjia Technology Co., Ltd.**, Shenzhen (CN)

(**) Term: **15 Years**

(21) Appl. No.: **29/905,243**

(22) Filed: **Oct. 18, 2023**

(51) LOC (14) Cl. **23-06**
(52) U.S. Cl. **USPC D6/528; D6/534**

(58) **Field of Classification Search**
